Patented Nov. 9, 1915.

UNITED STATES PATENT OFFICE.

WILLIAM H. SCHULTE, OF TRENTON, NEW JERSEY.

CARBURETER.

1,159,423.

Specification of Letters Patent.

Patented Nov. 9, 1915.

Application filed April 14, 1915. Serial No. 21,207.

To all whom it may concern:

Be it known that I, WILLIAM H. SCHULTE, a citizen of the United States, residing at Trenton, county of Mercer, and State of New Jersey, have invented certain new and useful Improvements in Carbureters, fully described and represented in the following specification and the accompanying drawings, forming a part of the same.

This invention relates to carbureters for internal combustion engines, the object of the invention being to provide a simple and efficient carbureter in which the fuel feed and air supply shall be controlled by the suction so as to assure the proper mixture at different speeds, and the supplemental air supply be increased and decreased in the proper manner so as to secure smooth and uniform running of the engine on all changes of speed.

A further object is to provide such a carbureter of cheap and convenient construction such as to be readily manufactured in large quantities and assembled readily for different installation connections, and with the parts readily accessible and removable for renewal or repair.

For a full understanding of the invention, a detailed description of a construction embodying all the features of the same in their preferred form will now be given in connection with the accompanying drawings forming a part of this specification, and the features forming the invention then specifically pointed out in the claims.

In the drawings:—Figure 1 is a vertical central section of the carbureter. Fig. 2 is a plan view of the same, partly broken away to show the starting air valve, and Fig. 3 is a plane lay out of the supplemental air valve flange.

In the drawings, A is a casting forming part of the mixing chamber and the outlet passage controlled by the usual disk throttle valve 10, and having the usual flange for connection to the engine.

B is the fuel reservoir having the usual inlet valve 11 controlled by float 12, and having the fuel feed passage 13, this chamber B being secured to the bottom of casting A by bolt screw 14 passing through the chamber and its cover 15. The cover 15 preferably carries the fuel supply passage with its connections and the inlet valve 11, so that these parts are independent of the

reservoir bowl and simply held together by the bolt 14, and it is thus possible to turn the cap 15 with the fuel supply connections to any point desired for convenience in connecting up the reservoir. The entire valve 60 construction, also, is thus separate from and independent of the bowl, which is convenient for manufacture, testing and assembling. A portion of the mixing chamber and the supplemental air inlet chamber is 65 formed by casting C preferably secured to casting A by bolt screw 16 passing through the mixing chamber and into spider or cross-bar 17, which seats against shoulder 1 on casting C to hold castings A, C together. 70 For the purpose of adapting the carbureter for engine connection either with the casting A vertical, as shown, or turned in either direction 90° for a horizontal connection, the mixing chamber portion of the casting 75 C is preferably made rectangular, as shown, and is provided with openings 8 in the bottom and each of its side walls for the screw bolt 14, so that the fuel reservoir B may be secured to the casting A in either of the 80 three positions, the two openings 8, which are not in use, being closed by screw caps.

The casting C is provided with a downward cylindrical extension 18, forming the primary air passage and inclosing nozzle 19, 85 which is screwed into casing B for connection of the nozzle passage with fuel supply passage 13. The nozzle 19 has a fuel opening 2 above the fuel level, and positioned so as to supply fuel for starting and low 90 speeds with their low suction, and an opening 3 at the top of the nozzle through which additional fuel is drawn on higher speeds and greater suction. As shown, a connection 20, for hot air supply, closes the lower 95 end of the air passage 18, but it will be understood that this is not necessary where hot air is not to be supplied, and that the air passage 18 may open directly to the atmosphere about the nozzle 19.

The casting C forming the supplemental air chamber, is provided with a circular opening in its top wall on which is secured a cap the lower rim 21 of which forms a valve seat for supplemental air valve 22 105 normally closed by coil spring 23 compressed between the valve and an abutment 24 secured on stem 25 upon which the valve slides freely and which extends upward through the top 26 of the cap and is screw- 110

threaded therein for adjustment of the tension of spring 23, and locked in position by lock-nut 27 clamping split hub 28 upon the stem. The valve 22 is provided with an upwardly-extending peripheral flange 4 having an inclined or curved cut off edge 5, this edge being shown as a helical or small pitch extending throughout the periphery of the valve, so that, as the valve 22 opens, 5 the lowest part of this cut off edge first passes the port and then the port is gradually opened by the flange in accordance with the suction and the pressure of spring 23 to secure a very gradual change of air 10 supply in accordance with changes of speed. The cap is provided with side walls 6 forming ports for the passage of air to the valve 22, and a rotary cover or air shut off valve 29 is mounted to rotate on the cap and provided with corresponding air ports 7, this 15 valve 29 being rotated by hand through actuating piece 30 and suitable connections, to move the ports 6, 7 out of line and thus close off the supply of air to the supplemental air valve for securing a rich mixture 20 in starting, as usual in automobile carbureters.

The cap with the supplemental valve and all the connected supplemental air valve 30 parts carried thereby is secured in place on the top of the casting C by screws 9.

It is found in practice that the flange 4, with the cutoff edge 5, secures a very smooth action of the engine on changes of speed, as 35 this edge may readily be formed to secure just the required action of the supplemental valve in connection with its pressure spring, the changes of air admission being thus made very gradual and in correct proportion 40 throughout the entire valve movement. It is important to use a supplemental air valve of large area for control by slight changes in suction, but such large valves give too much increase of valve area on 45 opening. The flange corrects this, so that a large valve may be used with any rate of change of air inlet area desired. The long stroke of the valve made possible by this flange, is important, also, in that it avoids 50 the use of all dash pot or check devices to retard the valve movement, as the valve remains substantially stationary between strokes of the engine cylinders, in accordance with its adjustment and the vacuum resulting 55 from the engine's speed, it being possible to use a light spring so that the pressure tending to close the valve is not so great as in other large supplemental valve constructions. It will be understood that, while 60 the flange with its cutoff edge has been shown as on the valve itself, the same result may be secured by forming the valve seat with a flange having such an edge passed by the valve in opening and closing.

65 It will be seen also that the carbureter is

very simple and cheap of manufacture, and that the arrangement of the fuel nozzle, with the main and supplemental air inlets, produces a most efficient and economical carbureter. The parts, also, are most convenient 70 of access and removal for renewal or repair. Thus the fuel reservoir with the nozzle may be withdrawn without interference with the other parts of the carbureter, by removing the bolt screw 14 and dropping the reservoir 75 with the nozzle 19 from the casting A and the air passage 18. The supplemental valve construction, also, is a complete unit, the cap carrying the entire supplemental valve construction, so that this part of the carbureter 80 may be assembled as a unit, and then inserted and secured in place by the screws 9 entering the top of casting C, and by removing these screws the whole supplemental valve construction may readily be removed for inspection and repair. 85

What is claimed is:

1. A carbureter having a supplemental air valve spring pressed and controlled by the carbureter pressure, and a port-closing 90 flange provided with an inclined or helical edge determining the rate of opening of the air inlet port during the movement of the valve.

2. In a carbureter, the combination with a 95 fuel nozzle having outlets at different levels, of a primary air inlet the air from which passes the lower outlet of the nozzle, a supplemental air inlet supplying air at or near the level of the upper outlet of the nozzle, a 100 supplemental air valve spring pressed and controlled by the carbureter pressure, and a port-closing flange provided with an inclined or helical edge determining the rate 105 of opening of the air inlet port during the movement of the valve.

3. In a carbureter, the combination with a fuel nozzle having outlets at different levels, of a primary air inlet the air from which passes the lower outlet of the nozzle, a supplemental air inlet supplying air at or near the level of the upper outlet of the nozzle, a supplemental air valve spring pressed and controlled by the carbureter pressure, a port closing flange provided with an inclined or 110 helical edge determining the rate of opening of the air inlet port during the movement of the valve, and a manually controlled valve for closing the supplemental air inlet. 115

4. In a carbureter, the combination with 120 a casing member A forming the mixing chamber and outlet to the engine, of fuel reservoir B suspended from casing A and carrying the fuel nozzle, casing member C secured to the side of member A and forming a supplemental air chamber and vertical air inlet passage 18 about the nozzle, and supplemental air valve mechanisms mounted on member C, substantially as described. 125

5. In a carbureter, the combination of cas- 130

ing member A by which the carbureter is secured to the engine, of fuel reservoir B having adjustable cover 15 carrying the fuel supply connection and fuel valve and secured to member A by central bolt 14, said member A being provided with openings in a plurality of sides for bolt 14, whereby member A may be turned for vertical or horizontal connection to the engine, and the

reservoir secured thereto, substantially as described.

In testimony whereof, I have hereunto set my hand, in the presence of two subscribing witnesses.

WILLIAM H. SCHULTE.
